UNITED STATES PATENT OFFICE

150,997

DESIGN FOR A LECTERN

Albert T. Long, Baltimore, Md.

Application July 24, 1947, Serial No. 140,489

Term of patent 14 years

(Cl. D33—10)

To all whom it may concern:

Be it known that I, Albert T. Long, a citizen of the United States, residing at Baltimore, in the county of Baltimore and State of Maryland, have invented a new, original, and ornamental Design for a Lectern, of which the following is a specification, reference being had to the accompanying drawing, forming a part thereof.

Figure 1 is a perspective view of a lectern, as viewed from the front, showing my new design.

Figure 2 is a similar view, as viewed from the rear.

I claim:

The ornamental design for a lectern, as shown.
ALBERT T. LONG.
